UNITED STATES PATENT OFFICE.

MICHAEL S. COLE, OF PHILADELPHIA, PENNSYLVANIA.

VALVE BOX.

Application filed July 27, 1922. Serial No. 577,829.

The object of my invention is to provide a novel valve box having many advantages and being particularly adapted for use in connection with the valves of the gas or water or other pipes which extend from the street mains into the houses or buildings of the individual users of the gas or water and which are buried in the ground beneath the street and its side walk.

10 The invention aims to provide a box of simple and efficient construction which may be readily placed around the valve and in which the valve may be quickly and properly centered and in which the body of the valve will be prevented from being accidentally turned relatively to the box and through which access may be had to the valve for the purpose of opening or closing the same from the level of the street or pavement.

15 A further aim of the invention is to provide a box whose vertical dimensions may be readily varied to suit different dimensions between valves and the level of the streets or side walks beneath which they are located.

The invention consists in the novel construction, combination and arrangement of parts hereinafter described and claimed.

In the accompanying drawings, illustrating the invention,

Figure 1 is a top view of a valve box embodying my invention and applied to a valve and its pipe, the valve and its pipe being shown by dotted lines.

35 Figure 2 is a side view, partly broken away and partly in section, of the parts shown in Fig. 1.

Figure 3 is a vertical section through the lower portion of the box, on line 3—3 of Fig. 2.

Referring to the drawings, 2 and 4 designate upper and lower telescope sections, respectively, which constitute the body of the valve box. The sections 2 and 4 are open at their upper and lower ends, and they may be of any suitable shape in cross section, preferably rectangular, as shown in the drawings.

50 The lower end portion of the lower box section 4 has vertical slots or openings 5 in opposite walls thereof for the reception of a horizontal pipe 6 which is provided with a valve 7 to be enclosed by and contained within the box. The valve 7 is of usual construction, having the hexagonal end portions 8 providing oppositely disposed flat surfaces 9

on the body portion of the valve, and having the usual plug 10 provided with the handle 11, by means of which the plug 10 may be turned to open and close the valve as desired.

55 The upper box section 2 is supported on the lower section 4 by two pins 12 arranged at diagonally opposite corners of the sections and extending through openings in the upper section 2 and resting in notches or grooves in the lower section 4. Each pin 12 is removable from the sections 2 and 4 and is adapted to be inserted into any one of a vertical series of notches or grooves 13 in the lower section 4 to support the upper section 2 in different positions of vertical adjustment thereon.

Opposite side walls of the lower portion of the lower section 4 adjacent to the sides of the valve 7 are provided with two horizontal screws 14 which are screwed into and through the same, as illustrated. The inner ends of the screws 14 carry two plates or parts 15 having flat surfaces adapted to engage the flat surfaces 9 of the body of the valve 7. The inner ends of the screws 14 are rotatably fitted in the parts 15 to permit the screws 14 to be turned without turning the parts 15; and the lower portions of the parts 15 have lips 16 formed thereon which extend beneath and engage the bottom of the valve body and prevent the parts 15 from turning with the screws 14. The outer ends of the screws 14 have suitable handles 17 pivotally mounted thereon by means of which the screws 14 may be conveniently turned to move the parts 15 toward or from the valve 7 to clamp or release the same, as desired.

95 In installing the box, the lower section 4 thereof is first placed centrally over the valve 7 with the slots 5 over the pipe 6, and the section 4 is then lowered relatively to the valve 7 to the position shown in the drawings, causing the pipe 6 to enter the slots 5 and the section 4 to enclose the valve 7. The screws 14 are then turned to move the parts or plates 15 toward each other to center the valve 7 within the box and to clamp it firmly between the parts 15. This done, the upper box section 2 is adjusted relatively to the lower section 4 by removing and replacing the pins 12 until the top of the upper section 2 is flush or substantially flush with the level of the street or side walk beneath which the valve 7 is lo-

cated. The dirt or earth is then filled in around the exterior of the box, which, thereafter, provides an open passage at all times for access to the valve 7 to open and close the same when desired. The top of the box may be closed by any suitable removable cap or cover plate.

The lips 16 on the plates or parts 15 not only prevent the parts from turning when the screws 14 are turned, but they also prevent accidental vertical displacement of the box relatively to the pipe 6 which is held firmly embedded in the earth.

The clamping of the body of the valve 7 between the parts 15 holds the valve stem 10 and its handle 11 in a vertical and upright position in which the handle 11 may be conveniently reached from above at all times, and prevents the accidental turning of the valve from its upright position by the pipe 6, should it be turned in repairing it or connecting fittings to the remote ends thereof.

I claim as my invention:—

1. A valve box provided with an open bottom and having vertically extending openings in opposite side walls thereof having open bottoms for the reception of a pipe, said box being adapted to receive and enclose a valve carried by the pipe, and means extending inwardly from opposite walls of the box at right angles to the axis of the pipe and being constructed to be adjusted to engage opposite flat sides of the valve to prevent it from turning relatively to the box, said openings and said means permitting the box to be lowered to and about the pipe and its valve from a position above the same.

2. A valve box provided with an open bottom and having vertically extending openings in opposite side walls thereof having open bottoms for the reception of a pipe, said box being adapted to receive and enclose a valve carried by the pipe, and means extending inwardly from opposite walls of the box at right angles to the axis of the pipe and being constructed to be adjusted to engage opposite flat sides of the valve to prevent it from turning relatively to the box, said openings and said means permitting the box to be lowered to and about the pipe and its valve from a position above the same, and said means having parts arranged to extend under the valve and prevent upward displacement of the box.

3. A valve box provided with an open bottom and having vertically extending openings in opposite side walls thereof having open bottoms for the reception of a pipe, said box being adapted to receive and enclose a valve carried by the pipe, and means extending inwardly from opposite walls of the box at right angles to the axis of the pipe and being constructed to be adjusted to opposite flat sides of the valve to prevent it from turning relatively to the box, said openings and said means permitting the box to be lowered to and about the pipe and its valve from a position above the same, and said means having a screw screwed into and through a side wall of the box and carrying a part on its inner end constructed to engage the valve.

In testimony whereof I affix my signature hereto.

MICHAEL S. COLE.
